UNITED STATES PATENT OFFICE

JERRY H. SIMUNEK, OF GREGORY, SOUTH DAKOTA

AUXILIARY AIR INLET FOR HUMIDIFIERS

Application filed January 21, 1926. Serial No. 82,886.

This invention relates to an auxiliary air inlet for use in humidifiers especially adapted for use in supplying moist air to the fuel charge before the fuel charge enters the combustion chambers of an engine and the important aim of the invention is to provide an attachment which may be easily applied without the exercise of unusual skill and without detaching many parts of the motor.

10 Other objects and advantages will be apparent during the course of the following description.

In the accompanying drawing, Figure 1 is a perspective of the attachment applied.

15 Figure 2 is a sectional view through the attachment applied.

Figure 3 is a vertical transverse sectional view taken on line 3—3 of Figure 2.

In the drawing wherein for the purpose 20 of illustration is shown a preferred embodiment of the invention, the numeral 5 designates a container for water and one side of the container is as shown in Figure 1 somewhat recessed or curved inwardly to conform 25 to the curvature of the adjacent portion of the motor. This permits the container to be positioned close to the motor so that the water is heated prior to being drawn into the intake manifold 6 as will be described.

30 Figures 1 and 2 illustrate that a gasket-like attaching member 7 is adapted to be positioned between the flanges 9 of the manifold and the carburetor and securely held in place by the bolts 10 or other fastening devices. The attaching member 7 is provided with a tapered combined neck and valve casting 11 having separate passages 12 communicating with the interior of the attaching member as shown in Figure 3 and receiving 35 ball valves 14.

In considering Figure 3 it will be seen that the ball valves are normally unseated and rest upon lower stop pins 15. Therefore when the motor is running at a rapid speed with the 40 throttle well open the suction or vacuum in the intake manifold will not be so great and the ball valves will remain open. On the other hand, when the motor is running slowly as for example when the throttle is slightly 45 open the vacuum in the intake manifold will

be substantially greater and the ball valves 14 will be drawn upwardly into engagement with the valve seats 16 in the upper portions of the passages 12 whereby to cut off or substantially reduce the supply of moist air to 55 the engine. Upper stop pins 15 are provided in the regions of the valve seats 16 to stop the valves 14 from seating so firmly as to become wedged in the seats 16, the stop pins however permitting the valves to accomplish 60 a sufficient closure. Thus, the supply of moisture will increase as the engine gains speed and heat and attains a condition to assimilate the moisture with resulting improved efficiency. 65

The valve casing has a branch 20 directly communicating with the container 5 to draw the moistened air from the same. Figure 2 very clearly illustrates that an inlet member 24 is extended through the top of the container and terminates adjacent the bottom of the same so that the air which is drawn through the container will be forced to travel upwardly through the water before it may be drawn into the manifold. The air thus drawn through the water is saturated with moisture and when supplied to the engine by way of the manifold will introduce moisture directly into the cylinders. 70

In carrying out the invention the inlet 80 member 24 may be provided with a screen 29 at any suitable place so as to prevent water from splashing out of the container.

With reference to the foregoing description taken in connection with the accompanying drawing it will be seen that the attachment may be easily connected to the internal combustion engine and more particularly to the fuel supply means therefor without materially altering the engine and without the exercise of unusual skill. The proximity of the container 5 to the crank case and the engine cylinders results in the transfer of a considerable amount of heat to the water so that vaporization is aided. 85

A humidifying device constructed in accordance with this invention is substantially automatic in its operation. There are few working parts to get out of order and by reference to Figure 3 it will be seen that by the 100

employment of the separate valves a more or less constant supply of humidified air is assured at the speeds which call for the supply of such humidified air. Relative to the stop pins 15, it will be seen that besides their limiting function relative to the valves 14 they serve to brace the valve casing 11 transversely against crushing or deforming influences, constituting a reinforcing medium for the casing.

Having thus described the invention what is claimed is:

In a device of the class described, a valve casing having a laterally flared wall portion at one end, said flared wall portion being adapted to be clamped between a pair of conduit sections for communication with the interior thereof, said casing having a valve chamber therein and having a passage extending through said flared wall portion, a partition terminating short of the bottom of said casing dividing said chamber into sections, each section having a valve and a seat therefor, transverse stop pins extending across said chamber above and below said valves for limiting movement of the valves and said pins holding said partition in position and reinforcing the same.

In testimony whereof I affix my signature.

JERRY H. SIMUNEK.
